Primary Examiner — Catherine A Tuttle(74) *Attorney, Agent, or Firm* — Belles Katz LLC(57) **CLAIM**

The ornamental design for a bubble machine, as shown and described.

DESCRIPTION

FIG. 1 is a front perspective view of a bubble machine showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an enlarged view of area 8 of FIG. 1.

The broken lines in the drawings illustrate portions of the bubble machine that form no part of the claimed design.

1 Claim, 8 Drawing Sheets(56)
